(57)

CLAIM

The ornamental design for an automobile, as shown and described.

DESCRIPTION

1.1 is a top, front and left side perspective view of an automobile showing my new design;

1.2 is a top, rear, and right side perspective view thereof;

1.3 is a front elevation view thereof;

1.4 is a rear elevation view thereof;

1.5 is a left side elevation view thereof;

1.6 is a top plan view thereof; and

1.7 is a bottom plan view thereof.

Portions of the automobile shown in broken lines are not part of the claimed design.
